United States Patent Office

Des. 192,487
Patented Mar. 27, 1962

192,487

HELICOPTER OR SIMILAR ARTICLE

David J. Nutting, Milwaukee, Wis., assignor to R. J. Enstrom Corporation, Menominee, Mich., a corporation of Michigan

Filed Jan. 19, 1961, Ser. No. 63,633

Term of patent 14 years

(Cl. D71—1)

FIGURE 1 is a side elevational view of a helicopter embodying my new design, the opposite side being substantially the same in appearance;

FIGURE 2 is a top plan view of the helicopter;

FIGURE 3 is a front elevational view of the helicopter; and

FIGURE 4 is a rear elevational view of the helicopter.

I claim:

The ornamental design for a helicopter or similar article, as shown and described.
